UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A PILLOW-BLOCK.

SPECIFICATION forming part of Design No. 32,591, dated April 24, 1900.

Application filed March 19, 1900. Serial No. 9,334. Term of patent 14 years.

To all whom it may concern:

Be it known that I, ANTONIO C. PESSANO, of the city and county of Philadelphia, in the State of Pennsylvania, have invented a new and original Design for Pillow-Blocks, of which the following is a specification.

My design for pillow-blocks is shown in the accompanying drawings, in which—

Figure 1 is a perspective view of a pillow-block embodying the design, and Fig. 2 is a plan view of the same.

A is a flat base upon which is located a centrally-disposed and longitudinally-arranged box B, projecting at either end, as at b b, beyond the ends of the base A, so that the sides of the base form lateral horizontal flanges a a. The projecting end b of the box B at one end is widened, as shown at B'.

C is the cover or top of the box, having its surface transversely arched and provided with a central boss c and longitudinal side flanges e. The portion F of the cap C at one end, which covers the widened portion B' of the lower part of the box, is correspondingly widened and has its upper surface curved or arched both longitudinally and transversely.

D D D D are four vertical column-like ex-

tensions from the sides of the box B and its cover or top C, which project outwardly upon the lateral sides a a of the base A. 30

The box and its cover C F are provided with a cylindrical longitudinal opening or passageway E, extending from end to end. The side flanges a a of the base A are provided with perforations f f, located between the columns 35 D D on each side.

The essential features of the design are the base A, with the longitudinally and centrally disposed hollow box B C F projecting therefrom at each end and having one end widened, 40 as at B' F, with the column-like lateral extensions D D from the box B C projecting laterally upon the sides a a of the base A.

What I claim as new, and desire to secure by Letters Patent, is— 45

The design for a pillow-block substantially as described and shown in the accompanying drawings.

In testimony of which invention I have hereunto set my hand.

ANTONIO C. PESSANO.
